UNITED STATES PATENT OFFICE

WILLIAM COOKE, OF BALTIMORE, MARYLAND

DESIGN FOR A SAFETY RAZOR BLADE SHARPENER

Application filed January 27, 1932. Serial No. 42,643. Term of patent 7 years.

To all whom it may concern:

Be it known that I, WILLIAM COOKE, a citizen of the United States, residing at Baltimore city, State of Maryland, have invented a certain new, original, and ornamental Design for a Safety Razor Blade Sharpener, of which the following is a specification, reference being had to the accompanying drawings, forming part thereof.

Figure 1 is a view in end elevation of the

safety razor blade sharpener showing my new design:

Figure 2 is a side elevation thereof, and
Figure 3 is a plan view.

I claim:

The ornamental design for a safety razor blade sharpener, as shown.

In testimony whereof I affix my signature.

WILLIAM COOKE.
